[57] ABSTRACT

A folding crank arm assembly is disclosed which is

particularly useful on a fishing reel, and more particularly a spin casting reel. The assembly includes a crank arm, crank knob, and crank knob carrier. The crank arm includes a hinge lock assembly comprising a pair of offset pivot ears having a single hole in each, a spaced pair of snap jaws, and a crank knob carrier having a locking offset which is received by the opposed locking jaws, and a pair of opposed pivot pins which are positioned for rotation within the holes in the pivot ears. When the knob is to be positioned in approximate parallel relationship with the crank arm, it is pressed along the longitudinal axis of the crank arm and the locking offset snaps free of the locking jaws and the knob swings into a pivotally remote position from its operative position. Reversely, when the knob is to be used, it is pivoted toward a position with its axis perpendicular to the crank arm and snap fittingly engages the offset jaws. A lock plate is also provided for lockingly engaging the crank knob carrier in its parallel relationship with the crank arm by snap fittingly overriding at least one of the pivot ears once the locking offset has been snap fittingly engaged by the offset jaws.

FOLDING CRANK ARM ASSEMBLY

CROSS REFERENCE TO RELATED
APPLICATIONS

The subject folding crank arm assembly is particularly useful in a spin casting outfit of the character disclosed in United States Patent Application Ser. No. 269,815 filed July 7, 1972, now abandoned, relating to a product sold by applicant's assignee under the trademark "POCKET FISHERMAN".

BACKGROUND OF THE INVENTION

1. Field of Invention

The subject folding crank arm assembly relates to cranks in general which are manipulated by hand to rotate any product. The same finds particular usage in connection with fishing reels, and is specifically adapted to spin casting reels.

2. Prior Art

Traditionally a crank arm assembly for fishing reel, or spin casting reel, includes a crank arm, a crank knob, and a crank knob rivet which pivotally and fixedly secures the crank knob to the crank arm. The crank arm is secured to the host fishing reel by means of a knurled thumb nut and removed from the fishing reel by means of removing the knurled thumb nut and removing the handle. Quite obviously, when one is fishing, and the nut becomes loose, and the fingers are cold, the nut may drop off and the reel is rendered useless. It is much more advantageous to have the crank arm more permanently secured to the reel, and when wishing to render the unit more compact for carrying, to provide for swiveling the crank knob into a position out of the way. This becomes particularly desirable in the product known as "POCKET FISHERMAN" which is the subject of U.S. Patent Application Ser. No. 269,815 filed July 7, 1972 as set forth above.

SUMMARY

The present invention seeks to provide a folding crank arm assembly for use on a spin casting reel, and more particularly where the spin casting reel is encased in a housing having a rod extending from one direction, and a closed C-shaped handle extending from the other direction. By providing the crank arm with a hinged lock assembly, and the knob with a carrier having a locking offset which engages a pair of opposed yieldable locking jaws on the crank arm, and is secured by means of a pair of pivot ears on the crank arm to a pair of pivot pins on the carrier, the knob may be swiveled into a position substantially parallel and beneath the crank arm by pivoting the same and releasing it from the yieldable locking jaws. In addition, once the crank knob carrier has been swiveled into its use position such that the locking offset has been engaged by the pair of opposed yieldable locking jaws on the crank arm, a pivotal lock plate including a curvilinear lock flange may be pivotally swung into position by overriding at least one of the pivot ears, thereby to retain the locking offset in snap fitting engaged position with respect to the opposed locking jaws on the crank arm.

One of the principal objects achieved by the present invention is to provide a folding crank arm assembly which can be more permanently secured to a fishing reel than the present construction in which a thumb nut is employed for securing the crank arm to the fishing reel.

A related and most important object of the present invention is to provide a folding crank arm assembly in which the crank knob, when used particularly in connection with the "POCKET FISHERMAN" spin casting fishing rig of U.S. application Ser. No. 269,815 filed July 7, 1972, will render the same more compact for carrying either in the clothing of the fisherman, or encased in a briefcase glove compartment of a car, suitcase, or any other close quarters for storage or transporting.

Still another object of the present invention is to provide a folding crank arm assembly highly useful in connection with a spin casting reel, the cost of which is only modestly increased over a fixed crank arm assembly, and yet affording and achieving all the objects of the invention as set forth above.

Still another object of the present invention is to provide a folding crank arm assembly useful particularly with a fishing reel which can be substituted for an existing crank arm assembly, either in original manufacture or by way of retrofit.

DESCRIPTION OF DRAWINGS

Further objects and advantages of the present invention will become apparent as the following description of an illustrative embodiment proceeds, taken in conjunction with the accompanying drawings in which:

FIG. 1 is an exploded perspective view of the subject folding crank arm assembly.

FIG. 2 is a top view of the folding crank arm assembly illustrating in phantom lines the crank knob and crank knob carrier in the retracted position.

FIG. 3 is a transverse sectional view showing the relationship in the releaseably locked position between the crank knob carrier and the crank arm taken along section line 3-3 of FIG. 2 but enlarged scale.

FIG. 4 is a plan view of the crank arm.

FIG. 5 is an end view of the crank arm.

FIG. 6 is a plan view of the crank knob carrier.

FIG. 7 is a front elevation of the crank knob carrier.

FIG. 8 is an enlarged view of the pivot pins on the crank arm carrier taken from the area designated by the circle 8-8 in FIG. 7.

FIG. 9 is a view of a product sold in the trade as the "POCKET FISHERMAN" the subject of U.S. application Ser. No. 269,815 filed July 7, 1972, illustrating the utility of the subject folding crank arm assembly on that device.

FIG. 10 is a top view of the same fishing rig shown in FIG. 9 illustrating the folding crank arm assembly with the crank knob in the retracted position.

FIG. 11 is a top view of a typical spinning reel mounted to a rod illustrating a two position configuration utilization of the subject folding crank arm assembly and how the dimensional space required for the reel can be reduced by folding the crank knob carrier and knob into the retracted or out of action configuration.

FIG. 12 is an exploded perspective view of the subject folding crank assembly including the lock plate and its relationship with respect to the crank arm and knob;

FIG. 13 is a perspective view showing the crank arm, crank knob carrier, knob, and lock plate in assembled relationship with the knob carrier pivotally secured in its use position;

FIG. 14 is a side elevational view, partly in cross-section, showing the relationship between the crank

knob carrier, hinge lock assembly, pivot ears, and lock plate;

FIG. 15 is a side elevational view showing the details of construction of the lock plate;

FIG. 16 is a top view showing the details of construction of the top of the lock plate;

FIG. 17 is a side elevational view taken from the opposed side with respect to FIG. 15 and showing the relationship of the locking flange with respect to the lock plate as well as release wing portion of the lock plate; and,

FIG. 18 is an end elevational view illustrating the configuration of the lock plate including the locking flange and release wing portions thereof.

DESCRIPTION OF PREFERRED EMBODIMENT

The folding crank arm assembly of the subject invention will best be understood by referring to a typical usage in a fishing rig such as illustrated in two examples and FIGS. 9 through 11 inclusive. Turning to the latter, FIG. 11, it will be seen that a fishing rig 1 is shown in top elevation which has a fishing rod at its forward or left hand portion, and a handle at the right hand portion. A fishing reel 5 is mounted in the center and is supplied with a retractable handle assembly 10. As will be observed, the crank knob 12 may be positioned in a retractable configuration closely adjacent the handle 3 of the fishing rig 1, or extended into the operative configuration such as shown in the phantom lines in FIG. 11. In the retracted position, the crank knob 12 is less likely to snag on loose fishing line, hooks, clothing, or other fishing paraphernalia.

Still another useful environment for the folding crank arm assembly is illustrated in FIGS. 9 and 10 where it is shown used in conjunction with a fishing rig 1 sold to the trade and generally known as the "Pocket Fisherman" spin casting outfit, the subject of U.S. patent application Ser. No. 269,815 filed July 7, 1972. There it will be seen that the fishing reel (unshown) is hidden within the housing 6, and the handle 3 is a closed C shape member leaving a handle opening 4 in the center. As illustrated particularly in FIG. 10, the crank knob 12 can be retracted into closed juxtaposed relationship with the open handle 3, and thus does not have to be disassembled from the fishing reel 5 to compact the same for the carrying configuration when out of use. Thus, in two separate types of fishing rigs, it will be seen that a folding crank arm assembly 10 such as illustrated which permits the crank knob 12 to be retracted finds significant utility and desirable application. In both instances, removal of the crank arm nut 7 is not required in order to position the crank knob 12 in its inactive or folded configuration. Recognizing that the folding crank arm assembly has the useful application wherever the same may be secured by means of a crank arm nut 7, or similar equivalent fastening device to a fishing reel, it will be seen that the elements which make up the folding crank arm assembly 10 as shown in FIG. 1 are simple, easy to operate, and inherently inexpensive and economical.

As will be seen in FIG. 1, the folding crank arm assembly includes a crank arm 11 which is secured by means of the mounting hole 24 to the fishing reel 5. The nut 7 (not shown in FIG. 1) is conveniently employed for that purpose. The crank knob 12 is secured by means of the knob rivet 29 to the crank knob carrier 14. The rivet is secured to the knob mount offset 30 of

the crank knob carrier at a position remote from the pivot pins 28 which extend from the locking offset portion 19 of the crank knob carrier 14. The crank arm 11 is provided at one end with the mounting hole 24 which as stated above, may be secured to a fishing reel 5 by means of an arm mounting nut 7. Remote from the mounting hole 24, provision is made for a hinge lock assembly 15 to removably secure the crank knob carrier 14 and crank knob 12 as an extension of the hinge lock assembly offset 21. This is achieved by means of pivot ears 16 which depend from the hinge lock assembly offset 21, and are provided with pivot ear holes 18 to receive the pivot pins 28 of the crank knob carrier 14, and when the crank knob carrier 14 is pivoted, the opposed snap jaws 20 secure the same by grasping the lateral edges of the locking offset 19 of the crank knob carrier 14.

In more specific detail, noting particularly FIG. 3, it will be seen that the locking offset 19 must pass through the centrally bent snap jaws 20. The snap jaws 20 are provided with a radius 25 at their central ends in order to pass the locking offset 19 into its nested configuration as shown in FIG. 3.

The relationship between the various offset members is illustrated in FIG. 2 where it will be seen that the offset reel mount 22 and hinge lock assembly offset 21 provide for clearance (see particularly FIGS. 10 and 11) so that the hand of the user grasping the crank knob 12 and rotating the folding crank arm assembly 10 will be free of the fishing rig 1. In carrying the fishing rig 1 when out of use, the very reverse is required.

This is achieved by moving the crank knob 12 into the configuration shown by the phantom lines in FIG. 2, where it is shown how the crank knob 12 is pivoted downwardly into the storage position. The knob mount offset 30 on the crank knob carrier 14 in conjunction with the locking offset 19 thereof, provides for a mounting of the knob 12 in the configuration shown in FIG. 2 as though the knob carrier 14 were an integral part of the hinge lock assembly offset 21 of the crank arm 11.

The relationship between the pivot ears 16 which receive the pivot pins 29 of the crank knob carrier 14 is shown in FIGS. 7 and 8. These are secured within the pivot ears 16, and more specifically in the pivot ear holes 18. Advantageously the pivot pins 28 when formed by stamping the crank knobs carrier 14 are given the octagonal cross section as shown in FIG. 8. This cross section proves desirable since it is economical to form from a stamping, and provides for point contact at several contact points thereby mounting the crank knob carrier 14 for a rolling type or pivoting type folding away from the hinge lock assembly 15.

It becomes apparent that the two principal elements of the folding crank arm assembly 10 are the crank arm 11 and knob carrier 14, both of which can be formed from stampings of either stainless steel, or other durable metal which is plated. The crank knob 12 is of standard construction, and secured to the crank knob carrier 14 by means of the knob rivet 29. As compared with a standard or conventional crank arm, only one additional part is required, the balance of the members being formed to define the hinge lock assembly 15 at the end of the crank arm 11 the crank knob carrier 14 being the additional part.

With reference to FIGS. 12 through 18 of the drawings, the details of construction of the lock plate 35,

and its relationship with respect to the crank arm assembly 10 is illustrated. With specific reference to FIG. 12 of the drawings, the lock plate 35 includes a base platform 37, having a mounting aperture 39, positioned adjacent the forward end of the platform 37. In the assembled position, the knob rivet 29 passes through the crank knob 12, mounting aperture 39, and then through the mounting aperture provided in the locking offset 19. As assembled, the lock plate 35 is freely pivotable about the knob rivet 29. It is also apparent that the base platform 37 of the lock plate 35 is interposed between the knob 12 and the knob mount offset 30.

The lock plate 35 further includes a peripheral skirt 41 depending from one of the lateral edges of the lock plate 35, in the manner shown in FIGS. 12 and 14 of the drawings. The peripheral skirt 41 extends downwardly for a distance and terminates in an inwardly turned curvilinear locking flange 43, the curvilinear construction of the locking flange 43 being designed so as to snap fittingly engage the corresponding pivot ear 16 positioned on the same side of the hinged lock assembly offset 21 which corresponds with the peripheral skirt 41. The opposed lateral edge of the lock plate 34 includes a release wing 45 which functions for a purpose to be more fully described hereinafter.

The details of construction of the lock plate 35 are illustrated in FIGS. 12 through 18 of the drawings.

With reference to FIGS. 12 and 13 of the drawings, the relationship of the lock plate 35 with respect to the crank knob carrier 14, hinge lock assembly 15, and hinge lock assembly offset 21 is illustrated. As noted above, the lock plate 35 is pivotally secured intermediate the crank knob 12 and the crank knob carrier 14 by having the knob rivet body 29 pass through the knob 12 rivet shoulder, mounting aperture 39, and through the mounting hole 39, in the knob mount offset 30. The vertical distance between the lower surface of the base platform 37, and the uppermost portion of the locking flange 43 is slightly less than the overall vertical height measured from the top of the hinge lock assembly offset 21, and the lower edge of the pivot ear 16. Due to these size dimensions, as well as to the curvilinear configuration of the locking flange 43, a snap fit relationship is achieved between a corresponding pivot ear 16, and the locking flange 43 of the lock plate 35, thereby to achieve the locking position for lockingly engaging the crank knob carrier in its use position with respect to the hinge lock assembly offset 21 in order to release the crank knob carrier 14 from locked engagement with respect to the hinge lock assembly offset 21, the operator need only press against the release wing 45 in the direction toward the peripheral skirt 41, causing the curvilinear locking flange 43 to ride over the corresponding pivot ear 16 and moving the lock plate 35 in an arcuate path out of the locked position. Once the lock plate 35 has been moved out of locked position with respect to the hinge lock assembly offset 21, the crank knob carrier 14 may be disengaged from the yieldable snap jaws 20 in the manner previously described, and the crank knob carrier 14, then folded into its storage position.

The significance of the particular construction and configuration of the lock plate 35, resides in the details of construction whereby the peripheral skirt 41 is disposed along the peripheral edge of the lock plate 35, which in use, parallels the direction of the application

of effort by the operator. In other words, once the crank knob carrier 14 has been pivoted upwardly into its locked position with respect to the hinge lock assembly offset 21, and as the operator commences using the fishing rig 1 and turning the crank knob 12 in a clockwise direction in the manner employed during the fishing operation, this motion or effort presses downwardly against the peripheral skirt 41 tending to maintain or tighten the lock relationship between the curvilinear locking flange 43 and the pivot ear 16. Hence, the clockwise rotational movement of the folding crank arm assembly has the tending to maintain the lock plate 35 in its locked relationship with respect to the hinged locked assembly offset 21. Clearly, if the peripheral skirt 41 and locking flange 43 were positioned on the opposed peripheral edge of the lock plate 35, the reverse operative forces would be in effect, and it would be difficult, if not impossible to maintain a locked relationship between the lock plate 34, and the hinge lock assembly offset 21, assuming that the reel assembly operates by moving the crank arm assembly 10 in a clockwise direction.

Furthermore, it will be observed that the release wing 45 is provided along the lateral edge opposed to the positioning of the peripheral skirt 41 such that when the operator wishes to release the lock plate 35, he may position his thumb along the outside surface of the release wing 45, and press against the normal effort of the curvilinear configuration of the locking flange 43 with respect to the pivot ear 15 causing the locking flange 43 to ride over the pivot ear 16 into its unlocked position. The positioning of the operator's thumb relative to the release wing 45 is shown in phantom in FIG. 14 of the drawings.

Hence, to release the crank knob carrier 14 from the hinge lock assembly offset 21, the lock plate 35 is ridden out of its locked position to permit the crank knob carrier 14 to be pivotally disengaged with respect to the yieldable snap jaws 20 and moved downwardly into its storage position.

The lock plate 34 may further include additional optional features if desired. It is quite well known to those engaging in the fishing sport that in most reel assemblies the knob generally has a loose fit with respect to the knob rivet 29. It is generally assumed that this loose fit must be maintained in order to ensure that the greatest relative degree of rotational movement is afforded the knob when attempting to use the reel. However, it is believed that in many cases, the knob is so loosely positioned on the knob rivet that oftentimes breakage occurs or alternatively, the knob may easily become disengaged from the knob rivet. In the optional embodiment envisioned herein, the forward end of the base platform 37 of the lock plate 35 may be provided with an upwardly curved curvilinear cross section, such that when the lock plate 35 is interposed between the knob 12 and the knob mount offset 30, the upper surface of the base platform 37 will function as a leaf spring relative to the knob 12. This is especially so if the lock plate 35 is made from a yieldable material such as leaf spring steel, or the like. In this manner, a sufficient amount of looseness may be retained in the knob 12, without at the same time permitting so much looseness that the knob 12 may easily become damaged or disengaged from the knob rivet 29.

While the foregoing description has proceeded on the assumption that the crank arm 11, crank knob car-

rier 14, and rivet 29 are metallic, the invention contemplates also the same general configuration but molded from plastic, or formed from pressed powdered metals, or combinations thereof. The reference to metal stamping is made because of economy, durability, and close proximity to retrofit or application to existing comparable crank arm.

Although particular embodiments of the invention have been shown and described in full here, there is no intention to thereby limit the invention to the details of such embodiments. On the contrary, the invention is to cover all modifications, alternatives, embodiments, usages and equivalents of a folding crank arm assembly as fall within the spirit and scope of the invention, specification and the appended claims.

What is claimed is:

1. A folding crank arm assembly comprising in combination,
  - a crank arm,
  - a crank knob,
  - a crank knob carrier,
  - an offset provided on said crank knob carrier proportioned and oriented to position the crank knob in the operative position with its base approximately parallel to the crank arm,
  - a hinge lock assembly provided at one end of the crank arm,
  - a lock plate,
  - means for pivotally mounting said lock plate in interposing relationship between said crank knob and said crank knob carrier,
  - said lock plate including lock means for locking said crank knob carrier in engaged position with regard to said hinged lock assembly,
  - means for mounting the crank arm to a rotatable member at that portion opposed to the hinge lock assembly,
  - a pair of opposed pivot ears on the end of the crank arm having apertures to receive pivot pins on the carrier,
  - pivot pins on the carrier for inserting and swiveling

the same within the pivot ears of the crank arm, and a pair of opposed yieldable jaws on a portion of said crank arm remote from said rotatable member and proportioned and oriented to yieldably receive and removably secure the crank knob carrier.

2. In the folding crank arm assembly of claim 1 above,

said remote portion of the crank arm being offset to mount the crank knob at a position remote from its attachment to the rotating member.

3. In the folding crank arm assembly of claim 1, said crank arm being proportioned for use with a spin casting reel,

a slot provided in an aperture at the end of the crank arm remote from the crank knob, and said means for mounting the crank arm to a rotatable member comprising a threaded element for screw threadedly mounting the crank arm to said rotatable member.

4. In the folding crank arm assembly of claim 1 above,

said lock means comprising a curvilinear inwardly turned locking flange for snap-fittingly engaging at least one of said pivot ears on the end of said crank arm.

5. In the folding crank arm assembly of claim 4 above,

said curvilinear locking flange being positioned along the side edge of said lock plate, such that the rotational effort applied to said folding crank arm assembly will tend to retain said lock plate in locked position with respect to said hinge lock assembly.

6. In the folding crank arm assembly of claim 1 above,

said lock plate further including a release wing positioned in opposed relation with respect to said lock means, thereby to provide means for releasing said lock plate from its locked position to an unlocked position.
